DESIGN FOR A COMBINED BRACELET AND
DETACHABLE WATCH CASING

Markus Geduldig, New York, N. Y.

Application January 18, 1947, Serial No. 136,226

Term of patent 3½ years

(Cl. D42—8)

To all whom it may concern:

Be it known that I, Markus Geduldig, a citizen of the United States of America and residing in the city, county, and State of New York, have invented a new, original, and ornamental Design for a Combined Bracelet and Detachable Watch Casing, of which the following is a specification, reference being made to the accompanying drawing, forming a part thereof.

Fig. 1 shows a top plan view of the combined bracelet and detachable watch casing, showing my new design.

Fig. 2 is an edge view of the combined bracelet and watch casing as illustrated in Fig. 1.

Fig. 3 is a bottom plan view of the combined bracelet and watch casing as seen in Fig. 1.

Fig. 4 is a top plan view of the combined bracelet and watch casing, the casing being detached therefrom.

Fig. 5 is a side elevational view of the watch casing per se.

The links of the bracelet shown in full lines are repeated throughout the length of the bracelet, as indicated by the broken line showing.

I claim:

The ornamental design for a combined bracelet and detachable watch casing, substantially as shown and described.

MARKUS GEDULDIG.
